UNITED STATES PATENT OFFICE.

ISAAC BROKAW AND WESLEY BUTLER, OF LITCHFIELD, ILLINOIS.

STRAW-STACKER.

SPECIFICATION forming part of Letters Patent No. 319,553, dated June 9, 1885.

Application filed October 13, 1884. (No model.)

To all whom it may concern:

Be it known that we, ISAAC BROKAW and WESLEY BUTLER, of Litchfield, in the county of Montgomery and State of Illinois, have invented a certain new and useful Improvement 5 in Straw-Stackers, of which the following is a full, clear, and exact description, reference being had to the accompanying drawings, forming part of this specification, and in 10 which—

Figure 1 is a side elevation of the stacker mounted on a truck. Fig. 2 is a transverse section taken on line 2 2, Fig. 1, looking toward the truck. Fig. 3 is an enlarged detail 15 longitudinal section of the adjusting-tubes. Fig. 4 is an elevation viewed from the machine end of the apparatus. Fig. 5 is a plan view, the elevating-frame being omitted. Fig. 6 is a top view with the elevating-frame in 20 place. Fig. 7 is a transverse vertical section taken on line 7 7, Fig. 5. Figs. 8 and 10 are detail sections in plan taken on line 8 10, Fig. 7, showing the parts in different positions. Fig. 9 is a detail vertical section taken on line 25 9 9, Fig. 8. Fig. 11 is a similar view taken on line 11 11, Fig. 10. Figs. 12 and 13 are enlarged detail views, more particularly referred to hereinafter. Fig. 14 is a vertical section on the line 14 14, Fig. 7.

30 Our invention relates to a straw-stacker, which may be connected to the thrashing-machine, or may be mounted on a truck, as shown.

Our invention consists in features of novelty, hereinafter fully described, and pointed 35 out in the claims.

Referring to the drawings, A represents the elevator-frame made in two parts, A' A², to which are secured tubes A³ A⁴, those A⁴ telescoping those A³, or vice versa, and being adjusted in and out, to lengthen and shorten the 40 frame, by sprocket or rag wheels B, engaging perforations A⁵ in the tubes A⁴ A⁴, (see Fig. 3,) and being secured to a shaft, B', journaled in boxes B², made fast to the part A' of the frame. 45 (See Figs. 1 and 2.) The shaft B' is turned to shorten or lengthen the frame by means of a shaft, B³, connected to the shaft B' by miter-wheels B⁴, and having a crank, B⁵, by which it can be turned. This shaft is journaled in 50 boxes B⁶, secured to the part A' of the frame.

A⁶ represents clips connecting the two parts of the frame.

When the machine is at work, the frame is lengthened out, as shown in Fig. 1, and when the machine is being transported from place 55 to place the frame is shortened up, as shown by dotted lines, Fig. 1, when the raddle will be received by a box, B⁷, secured to the truck. (See Fig. 1.)

The raddle C consists of an apron, of fabric 60 or other suitable material, and cross-slats C'. The raddle thus consisting of a belt or apron, the chaff, &c., cannot fall through it, but is carried up and discharged over the end of the frame. It passes around rollers C² C³, journaled in the outer and inner ends of the frame, respectively, and is driven by a belt or chain, C⁴, passing round a pulley or wheel, C⁵, on one end of the shaft or roller C³, and around a pulley or wheel, C⁶, on a shaft, C⁷, journaled 65 in boxes secured to standards C⁹ of a bolster, C⁸, supported by a toggle-frame, D. This shaft C⁷ has another pulley or wheel, C¹⁰, that is connected by means of belt or chain C¹⁰ 70 with a pulley or wheel, C¹¹, on a shaft, C¹², supported by and extending half-way across the bolster, and having on its inner end a miter-wheel, C¹³, meshing into a similar wheel, C¹⁴, on the upper end of a vertical shaft, C¹⁵, which pivots the bolster to the toggle-frame. 80

On the shaft C¹⁵, beneath the bolster, is a miter-wheel, C¹⁶, engaged by a miter-wheel, C¹⁷, on the inner end of a shaft, C¹⁸, journaled in boxes C¹⁹, secured to the toggle-frame. On the outer end of this shaft C¹⁸ is a pulley or wheel, C²⁰, connected by means of a belt or chain, C²¹, with a pulley, C²², on one end of a driving-shaft, C²³, journaled to the truck, (see Figs. 1, 4, and 6,) and provided with a driving-pulley, C²⁴, that receives power from the machine or 85 elsewhere, and thus the raddle is driven. The elevator-frame is hinged to the standards C⁹ of the bolster C⁸ by the shaft C⁷, which passes through strips C²⁵, secured to the section A' of the elevator-frame. The rear end of the elevator-frame is held down to support its outer end by a hanger, C²⁶, having a friction-roller, C²⁷, that engages beneath a circular rail, C²⁸, secured to the toggle-frame, and it will thus 90 be seen that the outer end of the elevator-frame will have free lateral movement, the bolster turning on the shaft C¹⁵, and the wheel or roller C²⁶ turning beneath the rail. The hanger C²⁶ is strengthened by brace-rods C²⁹. 95 100

The elevator-frame is raised and lowered by the toggle-frame as follows: This frame consists of a vertical part, D', inclined parts D² D³, and strips D⁴, connecting the inclined parts. 5 The inclined parts are pivoted at the upper ends to the vertical part at D⁵, and the lower end of the part D² is hinged to standards D⁶, secured to the truck, (see Fig. 1,) while the lower end of the part D³ is connected to the truck by means of pins D⁷, fitting in slots D⁸ of plates D⁹, bolted or otherwise secured to the truck. (See Fig. 1.) The side pieces or strips, D⁴, are connected to the part D³ by bolts D¹⁰, fitting in slots D¹¹ in the side pieces. It will 10 now be seen that by pulling the lower end of the part D³ the elevator-frame will be raised, and it will also be seen that the outer end of the frame will be raised a much greater distance because of the track or rail C¹² (to which the 15 inner end of the frame is made fast by the hanger, as specified) being made fast to the side pieces, D⁴, which are connected to the part D³ midway between its upper and lower ends. The bolster and vertical part of the toggle-frame is of course raised as the lower end of the part D³ is pulled inward. As a means for 20 pulling the lower end of the part D³ inward we have shown ropes or chains H, connected thereto, and to a drum, H', or two rollers secured 25 to a shaft, as shown in Fig. 5, journaled in boxes secured to the lower end of the part D². The roller or shaft has a cog-wheel, H², engaged by a worm, H³, provided with a crank, H⁴. It is journaled in boxes H⁵, secured to 30 cross-pieces H⁶, made fast to the part D² above the wheel H². The ropes or chains H pass under friction-rollers D³⁰ on the lower part of the vertical member of the toggle-frame. (See Figs. 4 and 7.) At D³¹ are shown radius-rods which are parallel with the toggle-bars D², and which act in conjunction with said bars to keep the vertical toggle-frame D' in a vertical position, and at the same time admitting the vertical movement of said frame D'. 35 As the crank is turned the ropes or chains are wound upon the drum and the elevator-frame raised and lowered, as described. 40

We will now describe our improved device for giving to the elevator-frame a continual lateral-vibration while the machine is at work. 45 Surrounding the vertical shaft C¹⁵ where it passes through the bolster C⁸, and extending a little below the bolster, is a sleeve, I, (see Figs. 5, 7, and 14,) on which, beneath the bolster, is a cogged segment, J, and collars L L', having cams or projections L² L³, made adjustable by screws L⁴, passing through the collars and jamming against the sleeve. The sleeve, segment, and bolster are all connected, the 50 segment to the bolster by bolts I', (see Fig. 14,) so as to turn together. Meshing into the segment is a pinion, N', on the upper end of a vertical shaft, N, (see Fig. 7,) journaled in boxes secured to the vertical part of the toggle-frame. On the lower part of this shaft is a cog-wheel, N², engaged alternately by right and left worms, O' O², on a sleeve, O, which

is loose upon the shaft C¹⁶, but which is made to turn with it by the shaft being non-circular at this point, or by feather-and-groove connection. While the worm O' is in engagement with the wheel N² the elevator-frame will be swung in one direction through means of the described connection, and then when the worm O² is brought into engagement with the wheel N² the frame is swung in the other direction, and thus its vibration is kept up continually. The sleeve O is shifted to change the worms, as described, by means of a rock-shaft, P, with cogs P' P², (see Figs. 7, 9, and 80 11,) provided with a crank, P³, connected by a pitman or rod, T, to a crank, T', of a shaft, T², journaled in boxes T³, secured to a cross-piece, T⁵, on the vertical part of the toggle-frame. When the elevator-frame has been 85 swung to its limit in one direction, one of the cams, L² or L³, as the case may be, comes against a projection, U', on a vertical rock-shaft, U, journaled in the vertical part of the toggle-frame, turning it, and through means 90 of a lever, U², connecting-rod V, and arm V, with projections V², (see Figs. 10, 12, and 13,) turn the shaft T², and through it the shaft P, changing the worms, as described. The arm V is pivoted to the cross-piece T⁵, and the projections, as the arm is moved, come alternately against a crank, T⁶, on the shaft T² to rock the shaft. The crank T' of the shaft T² fits in a slot, T⁷, of the pitman T to allow a spring, W, to pull the shaft T² quickly in 100 either direction as soon as the pitman moves the crank T' over the dead-center. The spring W is connected to a crank, T⁸, on the shaft T² and to the cross-piece T⁵, and simply pulls the shaft either way after the pitman has 105 moved it, as described. The wheel N² may be raised out of contact with the worms by a clutch, X, and lever X', (see Fig. 11,) and when this is done the elevator-frame will not have this lateral vibration. 110

We claim as our invention—

1. In a straw-stacker, the elevator-frame made in two parts, in combination with the telescoping tubes and means for adjusting them, substantially as set forth. 115

2. In a straw-stacker, the elevator-frame made in two parts, in combination with the inner tubes, outer perforated tubes, sprocket-wheels engaging the perforated tubes, shaft to which the sprocket-wheels are secured, 120 shaft for turning the sprocket-shaft, and meter-wheels connecting the shaft, as set forth.

3. In a straw-stacker, the sectional adjustable elevator-frame and raddle, in combination with the truck and box secured to the 125 truck for holding the raddle when the elevator-frame is contracted, as specified.

4. In a straw-stacker, the combination, of the elevator-frame, the toggle-frame, bolster, circular track, hanger for connecting the rear end of the elevator-frame to the track, and means for adjusting the toggle-frame, substantially as set forth. 130

5. In a straw-stacker, the combination, with

- the elevator-frame and truck, of the toggle-frame consisting of a vertical part, inclined parts by which the vertical part is supported on the truck, side pieces connecting the inclined parts, one of the inclined parts being adjustable toward the other part, substantially as set forth. 5
6. In a straw-stacker, the combination, with the elevator-frame and truck, of the toggle-frame consisting of a vertical part, inclined parts, and side pieces, supports for the toggle-frame on the truck, and ropes or chains and drum by which one inclined part is adjusted toward the other part, substantially as set forth. 10
- 15 7. In a straw-stacker, the combination of the shaft C¹⁵, sleeve O' with right and left threads, shaft P with cogs P' P² and crank P³, pitman T, crank-shaft T', arm V with projections V², rod V', lever U², shaft U, projection U', shaft C¹⁸, sleeve I, collars L L', with cams L² L³, segment J, pinion N', shaft N, and cog-wheel N², all arranged and operating substantially as and for the purpose set forth. 25
8. In a straw-stacker, the slotted pitman T, crank-shaft T', in combination with the elevator-frame and devices, substantially as described, by which lateral vibration is imparted to the elevator-frame. 30
9. In a straw-stacker, the shaft C¹⁸, threaded sleeve O, sliding cog-wheel N², shaft N, clutch X, and lever X', in combination with the elevator-frame and devices, substantially as described, by which lateral vibration is imparted to the elevator-frame. 35
